COOKING VESSEL

Gordon T. Rosenlund, Savage, Minn., assignor to Minnesota Mining and Manufacturing Company, St. Paul, Minn.

Filed Dec. 14, 1970, Ser. No. 26,493

Term of patent 14 years

Int. Cl. D7—04

U.S. Cl. D44—15

FIG. 1

FIG. 2

FIG. 3

FIG. 4

FIG. 1 is a front perspective view of a cooking vessel showing my new design;

FIG. 2 is a top view thereof;

FIG. 3 is a side elevation view as seen from the left of FIG. 1, the opposite side view being a mirror image; and

FIG. 4 is a rear elevation view thereof.

I claim:

The ornamental design for a cooking vessel, substantially as shown and described.
